UNITED STATES PATENT OFFICE.

HENRY D. BOKOP, OF DEFIANCE, OHIO.

BOTTLE CRATE OR CASE.

1,132,157.

Specification of Letters Patent. Patented Mar. 16, 1915.

Application filed October 21, 1912. Serial No. 727,026.

To all whom it may concern:

Be it known that I, HENRY D. BOKOP, a citizen of the United States, residing at Defiance, in the county of Defiance and State of Ohio, have invented a new and useful 5 Bottle Crate or Case, of which the following is a specification.

The present invention relates to improvements in bottle crates or cases, one object of 10 the invention being the provision of a novel form of case or crate for the reception of bottled liquids in which the bottom has disposed thereupon a number of retainers so disposed that they coact one with another 15 and with the walls of the case or crate to receive the bottles, thus economizing in space and using every available portion of the bottom of the case or crate to support the bottles.

20 With the foregoing and other objects in view which will appear as the description proceeds, the invention resides in the combination and arrangement of parts and in the details of construction hereinafter described and claimed, it being understood 25 that changes in the precise embodiment of the invention herein disclosed can be made within the scope of what is claimed without departing from the spirit of the invention.

30 In the drawings Figure 1 is a longitudinal central sectional view through the crate or case constructed according to and embodying the present invention. Fig. 2 is a section taken on line 2—2 of Fig. 1 through the complete crate or case. Fig. 3 is a horizontal section taken on line 3—3 of Fig. 1. Fig. 4 is a perspective view of one of the bottle retainers *per se*. Fig. 5 is a detailed section showing the method of locking the lid or cover closed. Figs. 6 and 7 are detailed views showing modifications of the receptacle or 35 crate structure.

Referring to the drawings, the numeral 1 40 designates the bottom of the crate or case which is preferably made of sheet metal and has upstanding therefrom at the respective edges a single sheet of a similar metal which constitutes the walls 2 of the crate or case, 45 an angle iron 3 which is bent to conform to the contour of the edge of the bottom 1 being disposed to form a junction or connecting means between the lower end of the wall 2 and the edge of the bottom 1 and 50 being electrically welded together and to such portions of the crate or case as to make

a neat connection and to dispense with the use of rivets or other projecting connecting means.

Secured to and carried by the upper edge 60 of the wall 2 and surrounding the upper end of the crate is an angle iron 4, which is also electrically welded to the sheet 2 constituting the walls of the crate and electrically at opposite points are two short pieces 65 5—5' which constitute handles for the crate, said short pieces 5—5' being composed of pieces of angle iron.

The hinges 6 are connected to the rear edge of the wall 2 and carry the sheet metal 70 lid 7 which is disposed to rest flat upon the upper flange 4' of the angle iron 4, the lid carrying the flexible spring catch 8 whose free end is disposed to engage the rim 4', as clearly shown in Figs. 2 and 4, to hold 75 the lid closed. The cover or lid 7 is reinforced transversely at each hinge connection by means of the plates 9, as clearly shown in Figs. 1 and 2.

A number of bottle holders, as clearly 80 shown in Fig. 4, are properly connected to the bottom within the walls of the crate or case, and each consists of the two members 85 10—11 which are connected to the bottom by means of rivets 12 and are disposed in cruciform relation as clearly shown in Fig. 3, and each pair of such members are so disposed as to provide spaces therebetween which are also bottle receiving spaces wherein the bottle rests directly upon the bottom 1 while 90 the holders themselves retain the bottles between the projecting arms 14—14'. The upper terminal of each of the respective arms is provided with the downturned portions 95 15—15' against which the bottle is placed so as to spread the terminals and thus permit of the resiliency of such terminals to maintain the bottle within the holder or between the terminals in the spaces 100 13 upon the bottom 1 of the crate or case. By this arrangement the space for accommodating the bottles is lessened to a great degree, and a smaller crate in area will accommodate a greater number of bottles than the usual crate where cross pieces or rods are 105 employed.

It will be noted that by arranging the bottle holders or retainers as shown in Fig. 4 to accommodate 24 bottles, or what is termed a "crate," there are four longitudinal rows of three holders, the two holders adjacent the corners, having but two up-

standing arms which with the corners provide a receptacle for the bottles, while the holders adjacent the side walls, each have three upstanding resilient arms, the side wall displacing the fourth arm. It will also be noted that the holders in one row alternate relatively to those in the next row. Thus twelve holders attached to the bottom of the crate with the side walls and corners thereof provide in reality twenty-four bottle receptacles so that no space is lost, and the bottles in the spaces between the holders will be engaged by two or more of the resilient arms of the holders, just the same as if they were in the holders above the members 10—11 and not resting directly upon the bottom of the crate.

As clearly shown in Fig. 6, a lining 16 is disposed to the inner walls of the bottom 1 and wall 2, and thus provides a means to exclude to a great degree, the exterior temperature so as not to affect the bottled goods mounted in the respective holding spaces of the crate, such lining being composed of asbestos, or paper, while in Fig. 7 disposed in spaced relation to the bottom is a sub-bottom 1', and also disposed in spaced relation to the wall 2 is a sub-wall 2', the space between being filled with an insulating material 16' of the same character as the material 16 shown in Fig. 6. Otherwise in both structures, as shown in Figs. 6 and 7, the bottle holding devices and the other portions of the crate or case are identical. The

top is also insulated similarly to the bottom 35 and walls.

What is claimed is:

A bottle crate having mounted upon the bottom thereof within the crate, a plurality of bottle retainers, each retainer consisting of two U-shaped members, the terminals of which are curved to form resilient bottle engaging portions, the connecting portions of the members being disposed in cruciform shape and connected together and to the bottom of the crate, said retainers being arranged in a plurality of rows and spaced from each other, the retainers in one row alternating relatively to those in the adjacent rows to provide bottle receiving spaces between certain of the retainers and also certain of the retainers and the walls of the crate, the resilient terminals coacting with the bottles to maintain the bottles against movement, the curved portions of the terminals of each U-shaped member being bent so that one curved portion is inwardly while the other is outwardly thus providing bottle engaging means internally and externally of the holder.

In testimony that I claim the foregoing as my own, I have hereto affixed my signature in the presence of two witnesses.

HENRY D. BOKOP.
